United States Patent Office.

SAMUEL B. JEROME, OF NEW HAVEN, CONNECTICUT, ASSIGNOR TO SAMUEL PECK & CO., OF SAME PLACE.

Design No. 4,338, dated September 6, 1870.

DESIGN FOR A CLOCK-CASE.

The Schedule referred to in these Letters Patent and making part of the same.

To whom it may concern:

Be it known that I, SAMUEL B. JEROME, of New Haven, in the county of New Haven and State of Connecticut, have invented a new and original Design for a Clock-Case, of which the following is a specification, reference being had to the accompanying drawing.

The drawing represents a perspective view of the clock-case, which is polygonal in shape.

The edge *a* of the case, where the face and sides of the case meet, is beveled, as fully illustrated in the drawing, and has an ebony finish, in contradistinction to the body or face and sides of the clock, which are

usually finished or veneered with a wood of lighter color.

What I claim, and desire to secure by Letters Patent, is—

As a new and original design, a polygonal-shaped clock-case, with an ebony-finished bevel edge, as herein shown and described.

In testimony whereof I have hereunto set my hand, this 8th day of June, 1870, before two subscribing witnesses.

Witnesses: SAMUEL B. JEROME.
HENRY A. MIX,
ALGIE. B. CORBIN.
